UNITED STATES PATENT OFFICE

169,405

LAVATORY FAUCET SHELL

Stephen A. Young, Delphi, Ind.

Application January 28, 1953, Serial No. 23,331

Term of patent 14 years

(Cl. D91—3)

To all whom it may concern:

Be it known that I, Stephen A. Young, a citizen of the United States, residing at Delphi, in the county of Carroll, and State of Indiana, have invented a new, original, and ornamental Design for Lavatory Faucet Shell, of which the following is a specification, reference being had to the accompanying drawing, forming a part hereof, wherein:

Figure 1 is a top plan view of a lavatory faucet shell embodying my new design.

Figure 2 is a side elevation of the same looking toward the left in Figure 1.

Figure 3 is a front elevation of the same.

Figure 4 is a bottom plan view of the same.

I claim:

The ornamental design for a lavatory faucet shell, substantially as shown.

STEPHEN A. YOUNG.
